DESIGN FOR A BADGE

Frank S. Land, Kansas City, Mo.

Application November 24, 1947, Serial No. 142,786

Term of patent 14 years

(Cl. D29—11)

To all whom it may concern:

Be it known that I, Frank S. Land, a citizen of the United States, residing at Kansas City, in the county of Jackson and State of Missouri, have invented a new, original, and ornamental Design for Badge, of which the following is a specification, reference being had to the accompanying drawings, forming part thereof.

In the drawings:

Figure 1 is a face view of a badge, showing my new design.

Figure 2 is an edge view thereof.

I claim:

The ornamental design for a badge, as shown.

FRANK S. LAND.
